BITLESS HACKAMORE

Adam Pletsch, Spokane, Wash.

Application September 22, 1952, Serial No. 310,828

3 Claims. (Cl. 54—6)

1

This invention relates to new and useful improvements and structural refinements in hackamores.

One object of the invention lies in the provision of a bitless hackamore with which one may expeditiously and humanely train horses, particularly breaking in colts, as well as to effectively control trained horses.

Another object of the invention lies in the provision of a bitless hackamore which is so constructed as to lend itself for easy attachment to any head stall.

Another object of the invention lies in the provision of a bitless hackamore which is constructed with a minimum number of parts and thus adaptable to economical manufacture.

A still further object of the invention lies in the provision of a hackamore which very effectively controls a horse yet which is constructed to preclude any metal touching the animal and thus eliminating the possibility of injury to the horse.

These and other objects of the invention will become apparent during the course of the following description.

In the accompanying drawings, forming a part of this specification, and in which like numerals are employed to designate like parts,

Figure 1 is a perspective view of my improved hackamore and showing related portions of a head stall and a horse's nose by dotted lines;

Figure 2 is a longitudinal cross section taken through the lever and related pressure pad; and

Figure 3 is a transverse cross section taken as at line 3—3 of Figure 1.

Referring now more particularly to the drawings the numeral 5 indicates a U-shaped nose band formed from a strip of metal 6 bent back upon itself at the ends thereof to form transversely disposed sleeves 7. A supporting strip of leather 8 which is somewhat wider than the metal strip is secured in face to face engagement on the inner face of the metal strip as by rivets 9. Over the supporting leather 8 and disposed to contact the horse's nose, I have adheringly secured a strip of sheep skin 10 having the wool disposed inwardly. It will be understood that any suitable adhering means will be acceptable and also other cushioning means such as felt or foam rubber may be used. However, for the utmost in comfort for the horse I prefer sheep skin which permits limited air circulation between the contacting cushion and the horse's nose.

Engaged in the sleeves 7 are rings 11 which are square in plan and will be hereafter referred to

as squares to comply with the nomenclature of horsemen. The cheek straps 12 of a head stall are secured in the squares 11 and properly support the nose band on the horse's nose. Also secured in the squares 11 are adjustable loop straps 13 which are provided each with a buckle 14 at one end, and the free end is passed through its co-operating square and buckled by its buckle 13.

The opposed ends of the looped straps 13 each encircle one of a pair of spaced depending arms 15 which form parts of a lever 16 having a shaft 17 at right angles to and uniting the upper ends of the arms 15. Staples 18 form keepers for the straps and confine them at a fixed location longitudinally of the arms 15.

Each arm is provided with a depending rearwardly angled extension 19 which terminates in a rearwardly disposed horizontal terminal portion 20. In the terminal portions vertically disposed holes 21 are formed and rings 22 are loosely mounted therein for receiving and securing the forward ends of reins 23. When reins 23 are pulled rearwardly by the rider, the lower ends of the arms are moved and the crank pivots at 25 the fulcrum where straps 13 encircle arms 15, thus causing shaft 17 to move forwardly and because of the greater length of the arms and extensions 15 and 19 below the fulcrum, a lesser forward movement is supplied at the shaft 17, but greatly increased pressure is supplied.

To prevent the shaft 17 from touching and possibly injuring the horse's jaw, I have provided a pressure plate, indicated in general by the numeral 24. A sleeve 25 is loosely applied to the 30 shaft to permit rotation thereof and a longitudinally arcuate or outwardly bowed metal plate 26 is secured thereon as by welding or other suitable means.

A leather patch 27 is secured in covering relation to the inner face of said plate and is somewhat larger in plan than the plate. Adheringly secured over the inner face of the patch 27 is a cushion 28, shown to be felt, but which may be other suitable material having the desired body 40 consistency and firmness.

An aperture 29 is formed through the plate, patch and cushion midway the width thereof and adjacent the upper edge of plate 26.

A supporting strap 30 extends through the 45 aperture 29 and is buckled to itself by means of buckle 31 after having been passed about the head stall throat latch 32.

The pressure plate 24 being pivotally mounted permits the cushion 28 to assume any angle necessary to conform to the shape of the horse's jaw

upon which the hackamore is mounted for the time being. Since no metal engages the horse, the liability of injuring the horse is eliminated, yet sufficient pressure may be applied to properly control or train a colt or horse.

Having thus described my invention, I claim as new and desire to secure by Letters Patent of the United States:

1. A bitless hackamore for use with a head stall having check straps and a throat latch comprising a metal U-shaped nose band, a leather supporting strip secured to the nose band on its inner face, said strip being of a greater width than said band, a resilient material adheringly secured in face to face relation with the inner face of said supporting strip, transversely disposed securing sleeves one at each end of said nose band, squares one engaged in each sleeve, adjustable looped straps engaged through said squares, said cheek straps being engaged through said squares for supporting said nose band, a U-shaped lever having a shaft and spaced depending arms on the ends of the shaft and at right angles thereto, said arms extending intermediate their ends one through each said looped straps, staples in said arms and forming keepers for said straps, extensions on said arms and depending at a rearward incline and terminating in rearwardly disposed horizontal terminal portions, diametrically disposed vertical holes in said terminal portions, rein securing rings loosely engaged in said holes, a sleeve rotatably carried about said shaft, a plate carried by said sleeve and outwardly bowed longitudinally thereof, a leather supporting patch secured on the inner face of said plate, a resilient cushion adheringly secured on said patch and dis-

posed to contact the horse's lower jaw, an aperture extending through said plate, patch and cushion, and an adjustable supporting strap engaged through said aperture and adapted to engage said throat latch.

2. In a bitless hackamore, the combination with a nose band adapted to be supported by a head stall, straps on the nose band, a lever carried by said straps and adapted to receive reins at one end, said straps forming a fulcrum for said lever, whereby pull on said reins causes the lever to pivot, of a pressure pad pivotally carried by said lever at the other end of said lever and spaced from the fulcrum and adapted to apply pressure to a horse's jaw when the reins are pulled rearwardly.

3. In a bitless hackamore, the combination with a supporting harness, of a lever fulcrumed on said harness rearwardly of a horse's jaw and being adapted to receive reins at its lower end, and a pressure pad pivotally carried by said lever at the other end of said lever and spaced from the fulcrum and adapted to apply pressure to the horse's jaw when the reins are pulled rearwardly.
